UNITED STATES PATENT OFFICE.

GEORGE F. SIMONDS, OF FITCHBURG, MASSACHUSETTS.

DIE FOR MAKING ROLLED FORGINGS.

SPECIFICATION forming part of Letters Patent No. 358,628, dated March 1, 1887.

Application filed August 19, 1886. Serial No. 211,297. (No model.)

To all whom it may concern:

Be it known that I, GEORGE F. SIMONDS, of Fitchburg, in the county of Worcester and State of Massachusetts, have invented certain 5 Improvements on Dies for Making Rolled Forgings; and I hereby declare the following to be a full, clear, and exact description thereof, reference being had to the accompanying drawings, making a part of this specification, in 10 which—

Figure 1 is a perspective view of my improved die. Fig. 2 illustrates the die as formerly constructed and the waste of stock by its use, the change to my present invention 15 being shown in dotted lines. Fig. 3 is a section on line $x-x$ of Fig. 1, and an illustration showing the saving of stock.

My invention relates to dies such as are designed to be used in the machine for making 20 wrought-metal forgings described and shown in Letters Patent of the United States No. 319,752, issued to me June 9, 1885, and has for its object to produce a die which will reduce the waste of stock to a minimum and 25 at the same time, incidentally, greatly reduce the frictional strain on dies for making conical projectiles, my improved die being especially adapted for that purpose.

My invention is an improvement on the die 30 shown and described in United States Letters Patent No. 319,756, issued to me June 9, A. D. 1885; and it consists in providing that spreading-surface of the die where the base of the projectile is formed with an extended face 35 on such an angle as to closely approximate the line of the curve of the die which forms the point of the projectile, as will be hereinafter fully described, and specifically pointed out in the claim.

Practical experience demonstrated it to be 40 highly desirable that the waste of the stock in the use of dies made according to my Patent No. 319,756 should be reduced below the amount seemingly necessitated by the construction of such dies, the waste being about 45 in the proportion seen in Fig. 2. I discovered that by extending the spreading and reducing surface adjacent to the wall of the die which forms the base of the shot, so that it 50 merges with the plate of the die—say at about

an angle of twenty-five degrees—the end of the bar or stock will receive a preliminary conical rolling especially adapted to take the ultimate form of the projectile-point without any considerable waste of stock, this reduction of waste being shown in Fig. 3 in comparison to the waste, as shown in Fig. 2. 55

In order that those skilled in the art may make and use my invention, I will proceed to describe the exact manner in which I have carried it out.

In the said drawings, A is the die-plate or bed, a is the forming-surface of the die, and b b' are the walls of the die, all constructed after the manner described and claimed in my 65 hereinbefore-mentioned Patent No. 319,756.

The wall b' gives form to the base of the shot and cuts off the stock. As the wall b' rises to the point where decided work is being performed to shape the base of the shot, about 70 at d , the outer surface of the wall is projected, as seen at e , to meet the plane of the base A at about an angle of twenty-five degrees. This proportion is maintained as the wall b' rises gradually toward the finishing end f of the 75 die, where it will be found that the exterior or spreading surface e has reached such conformation as to leave the end of stock g in a conical shape closely approaching the exact form of the conical point of the finished projectile. The variation between the end of the stock as remaining after the rolling of a projectile and the precise form to be given such end to form the succeeding shot is shown in dotted lines on the stock C, Fig. 3. 85

In Fig. 2 is illustrated an end view of the conical shot-die as heretofore constructed and the change of form to my present invention indicated in dotted lines. In this same figure is illustrated, at h , the proportionate necessary 90 waste in the old form of die, and in Fig. 3, at i , is illustrated the small amount of waste in the operation of my present invention. The saving afforded by this new die in waste stock 95 will be therefore found a very material factor in the economical manufacture of conical projectiles.

The limited variations in the conical forms of the forward ends of the various kinds of conical projectiles should be followed in the 100

lines of the face *e* in making each variety of shot.

Having thus described my new invention, what I claim as new, and desire to secure by 5 Letters Patent, is—

A die for making rolled conical projectiles, provided with a forming-surface, *a*, reducing and spreading surfaces to form the point, and a reducing and spreading surface, *e*, to form

the base of the projectile and leave the end of 10 the stock in a form closely approximating the form of the point of a finished projectile, substantially as described.

GEO. F. SIMONDS.
